UNITED STATES PATENT OFFICE

2,492,406

PHYSIOTHERAPY DEVICE

Richard Thomas, Westwood Village, Calif.

Application July 9, 1946, Serial No. 682,412

11 Claims. (Cl. 128—33)

1

My present invention relates to a device for treating the human body, having a table or platform on which the patient lies with the portion of the body to be treated presented downwardly so that the treating portion of the device carried by or forming a part of the platform may act upwardly against the portion of the patient's body to be treated.

It is an object of the invention to provide a novel cooperation of parts in a single device whereby several cooperating modalities may be effectively applied to the body either simultaneously or separately. By use of the device rhythmic pressure waves of predetermined intensity may be applied to selected tissues of the body, and to these selected tissues vibratory waves or motion may be transmitted, of intensity determined by the operator of the device. The device is so arranged that during the application of either or both the rhythmic and vibratory waves, infra-red radiations may be applied.

A further object of the invention is to provide a therapy device having a base with a platform or table thereon, this platform having a portion which is translatable vertically with relation to the rest of the platform, so that this vertically translatable portion may be moved upwardly in engagement with a selected portion of the body, and pressure applying means below the platform adapted to apply through the vertically translatable portion of the platform to the patient controlled pressure waves of low frequency and high frequency determinable from the needs of the patient.

A further object of the invention is to provide in a device of the character set forth in the preceding paragraph means for producing relative horizontal movement of the platform and the pressure applying means so that different portions of the translatable portion may be acted on by the pressure applying means of the device.

A further object of the invention is to provide a device of this character wherein this relative movement of the platform and the pressure applying means may be controlled as to length or extent, thereby making it possible to concentrate the treatment at one point or to extend the treatment over a selected linear portion of the body. For example, with the patient supine upon the platform and the back of the patient resting upon the vertically translatable pad portion, the treatment may be limited to the lumbo-sacral articulations, may be extended from below the sacrum to the dorsal region, may be concentrated in the lower dorsal or upper lumbar region, or may be

2

limited to the upper dorsal region. Also, with the patient lying prone, the treatment may be limited to the abdominal region and the pressure waves may be caused to press either headward or footward. When the lateral tissues of the body are to be treated, the patient lies on his side.

A further object of the invention is to provide simple adjusting means for the operative parts of the device whereby the rhythmic and vibratory waves transmitted to the patient may be controlled so that they may range from extremely mild to full intensity, and whereby the application of the therapy may be caused to correspond to the size or extent of the area to be treated.

15 Further objects and advantages of the invention reside in a simple arrangement of parts whereby the platform may be moved on the supporting structure of the table and whereby the operative mechanism below the platform is yieldably and adjustably supported.

20 Further objects and advantages of the invention may be brought out in the following part of the specification.

25 Referring to the drawings which are for illustrative purposes only,

Fig. 1 is a perspective view of a preferred embodiment of my invention.

Fig. 2 is a plan view of Fig. 1 with the platform thereof removed.

30 Fig. 3 is a sectional view taken substantially as indicated by the line 3—3 of Fig. 2.

Fig. 4 is a sectional view taken substantially as indicated by the line 4—4 of Fig. 3.

Fig. 5 is a sectional view taken as indicated by the line 5—5 of Fig. 3.

35 Fig. 6 is an enlarged sectional view taken as indicated by the line 6—6 of Fig. 3.

Fig. 7 is an enlarged sectional view taken as indicated by the line 7—7 of Fig. 3.

40 Fig. 8 is an enlarged fragmentary sectional view taken as indicated by the line 8—8 of Fig. 3.

Fig. 9 is an enlarged fragmentary sectional view taken as indicated by the line 9—9 of Fig. 8.

45 Fig. 10 is an enlarged partly sectioned face view of one of the carriages, taken as indicated by the arrow 10 of Fig. 4.

As shown in the drawings, the therapeutic device includes a general supporting means consisting of a base 10 having front and rear walls 11 and 12 and end walls 13 disposed in vertical planes, these walls being joined at corners which project downward so as to form legs 14 for engagement with the floor. At the ends thereof the base 10 has top walls 15 and 16, best shown in Figs. 2 and 3. These top walls 15 and 16 coop-

erate with longitudinal rails 17 to define an opening 18 in the top of the base 10. Near their ends, the front and rear walls 11 and 12 have recesses 19 in their upper edges, the rails 17 are secured upon the upper edges of the front and rear walls 11 and 12 so as to extend across the recesses 19. The rails 17 are projected beyond the ends of the base 10 so as to provide handles 20 for convenience in moving the device which is so constructed that it is of relatively light weight. A platform 21 is supported upon the base 10 by means of four carriages 22 which engage these portions of the rails 17 which extend over the recesses 19 in the front and rear walls 11 and 12.

As shown in Figs. 4 and 10, each carriage 22 comprises a bracket 23 having a vertical outer wall 24, an upper shelf or horizontal wall 25 and a lower horizontal wall 26. The upper portions of the vertical walls 24 and the upper horizontal walls 25 of the brackets 23 are secured to the edges of the platform 21. In the space 27 between the upper and lower horizontal walls 25 and 26 of each bracket 23 upper and lower rollers 28 and 29 are supported respectively by upper and lower pillow blocks 30 and 31 in such position that the rollers 28 and 29 will engage the upper and lower surfaces of the adjacent portions of the rails 17. The lower pillow block 31 is supported on rubber bodies or washers 32 which act in expansion to press the lower roller 29 tightly against the rail 17 so that vibration of the carriages relatively to the rails 17 is prevented. It will be perceived that the circumferential faces of the rollers 28 and 29 are concave to correspond to the external curvature of the rails 17 which are made from metal tubing.

As shown in Figs. 3 to 7 inclusive, the platform 21 comprises a horizontal plate 34 and padded upholstering 35 covering the same and circumscribing the opening 33. As shown in Figs. 3 and 6, metal strips 36 are secured to the underside of the plate 34 of the platform 21 along the lateral edges of the opening 33, portions of these plates 36 projecting under the edges of the opening 33 so as to provide shelves 37. The platform 21 includes a vertically translatable wall portion 38 which occupies the opening 33. As shown in Figs. 1 and 6, this translatable wall portion 38 comprises a pad 39 having a longitudinal channel 40 corresponding to the spinous processes when the patient lies supine upon the platform in proper alignment with the pad 39. Below the pad 39, and attached thereto, the translatable wall portion 38 has transverse cleats 41 in side by side relation on the upper face of a belt 42 which extends longitudinally of the opening 33 and is of such width that its edges will engage the shelves 37 and thereby limit the downward movement of the translatable wall portion 38. The belt 42, as shown in Fig. 3, has its front end 43 secured to the plate 34 adjacent the head end of the opening 33. The opposite, or foot end 44 is attached to tension springs 45 for the purpose of holding the belt tight and permitting yieldability when a portion of the translatable wall portion 38 is raised, as shown in Fig. 3. The cleats 41 permit longitudinal bending of the translatable wall portion, but prevent lateral bending thereof.

The internal mechanism of the device includes a vertically movable supporting member 46 having the general characteristics of a lever, it being connected at one end by hinges 47 to the end wall 13 at the foot of the device, so that the head end 48 of the supporting member 46 may move

vertically. The head end 48 of the vertically movable member 46 rests on springs 49 of barrel-type. The lower ends of the springs 49 rest upon a plate 50 which is vertically adjustable for the purpose of varying the action of the springs 49, as will be hereinafter explained. The plate 50 includes a threaded boss 51 which receives the threaded lower end 52, Fig. 7, of a vertical shaft 53 which extends through an opening 54 in the head end 48 of the supporting member 46 and is hung from a thrust bearing 55, carried by the top wall 16 at the head end of the base 10.

The upper portion of the shaft 53 has fixed thereon a bevel gear 56 engaged by a bevel pinion 57 which is fixed on the inner end of the shaft 58. The shaft 58 projects through the front wall 11 of the base 10 and has thereon a hand wheel 59, rotation of which hand wheel 59 will rotate the shaft 53 and produce vertical movement of the plate 50. The upper and lower ends of the springs 49 are guided by vertical bars 60, the lower ends of which are threaded into the end portions of the plate 50, and the upper ends of which are slidably through openings in the transverse bar 61 comprising a portion of the head end 48 of the supporting member 46.

To indicate the compressive force or action of the springs 49 during the operation of the device, a bent arm 62, Fig. 7, is extended from the plate 50 to a belt 63 which runs over vertically spaced pulleys 64 and 65. The upper pulley 64 is fixed on a shaft 66 which projects through the front wall 11 of the base 10 and has thereon an indicator or pointer 67 adapted to traverse a dial plate 68 on the front face of the front wall 11. The lower pulley 65 rotates on a fixed shaft 69.

The means employed for application of intermittent upward force or pressure waves of relatively low frequency to the translatable wall portion 38 comprises a lobular member 70 fixed on a shaft 71 which is supported in bearings 72 on the vertically movable member 46. A sprocket 73, fixed on the front end of the shaft 71, is driven by a chain 74 from a drive sprocket 75 comprising a part of the power output mechanism of a reduction gear unit 76 which is also mounted on the member 46 and is driven by a motor 77.

A smaller drive sprocket 78 of the gear unit 76 through a chain 79 drives a larger sprocket 80 carried by a shaft 81 which is supported on the member 46 near its foot end by blocks 82. A crank pin 83, fixed on the sprocket 80, is connected by a link 84 with a pin 85 mounted on a lug 86 which projects laterally from a lever 87 which, as shown in Fig. 5, swings on a stub shaft 88 supported on the inner face of the front wall 11 near its lower edge. As shown in Figs. 8 and 9, the lever 87 comprises an undercut channel 89 forming a guide for a block 90 which is moved up and down the channel 89 by a screw 91 which lies in the channel 89. The lower end of the screw 91 projects below the lower end of the lever 87 and has thereon a handle 92 whereby it may be rotated. The block 90 has a projecting pin portion 93 to receive one end of a link 94, the head end of which is connected by means of pin 95 and a bracket 96 to the lower face of the plate 34 of the platform 21, as shown in Fig. 6. Rotation of the sprocket 80 transmits through the link 84 reciprocating motion to the lever 87. When the block 90 is raised above its lowermost position on the lever 87, it will transmit the swinging motion of the lever 87 through the link 94 to the platform 21, causing the platform 21 to move headward and footward on the base 10 as indicated by phantom

lines 97 and 98 in Fig. 3. Accordingly, the relative movement of the platform 21 and the force applying means represented by the lobular member 70 may be controlled by operating the handle 92 so as to screw the block 90 to the desired position along the lever 87.

For the purpose of transmitting vibration through the pad 39 to the patient I support on the member 46 near the head end thereof a sheave 99 carrying an eccentric weight 100. A small variable speed electric motor 101 drives the sheave 99 through a belt 102. The relatively high frequency vibration produced by the eccentric rotation of the weight 100 is transmitted through the member 46 and the lobular member 70 to the vertically translatable wall portion 38 of the platform 21 and is thereby imparted to the tissues of the patient which contact the pad 39.

The platform 21 carries a plurality of heating elements 105 of insulated resistance type. These heating elements 105 are placed in the upholstering 35 of the platform 21 around the opening 33. By this arrangement it is possible to transmit heat radiations in the infra-red rays to the body of the patient. The wiring to the electrical parts of the device has not been shown since conventional practices are followed. The control switches, etc. are all conveniently located on the front wall of the base as shown in Fig. 1. A timing switch 106 is provided, making it possible for the technician to place the patient under treatment which will be discontinued at the end of the period of time for which the timing switch 106 has been set. A switch 107 is provided for the vibrator drive motor 101, which switch is in series with a rheostat 108 whereby the speed of the motor 101 may be varied. The motor 71 is of constant speed reversible type and for its operation, a main switch 110 and a reversing switch 111 are provided.

The lobular member 70 has a plurality of lobes 115 equally spaced and of such width that they will pass between the shelves 37, as shown in Fig. 6. As the member 70 is rotated, these lobes 115 apply upward pressure impulses to the translatable wall portion 38. However, it is not intended that these impulses be sudden or abrupt in their action, but preferably that they shall be modulated. The lobes 115 press upwardly against the lower face of the belt 42 of the translatable member 38 with a force or pressure depending upon the position of the plate 50 which supports the lower ends of the springs 49. The head end 48 of the movable supporting member 46 is carried on the upper ends of the springs 49 and the downward reaction of the lobes 115 against the translatable wall portion 38 tends to force the member 46 downward so as to compress the springs 49. Conversely, therefore, the strength of the pressure applications of the lobes 115 in the translatable wall portion 38 will depend upon the position of the plate 50. In other words, if the plate 50 is raised, the reaction of the lobes 115 against the belt 42 will produce a greater compression of the springs 49 when the reaction of the lobes 115 forces the supporting member 46 downward, and this greater compression of the springs 49 is determinative of the upward pressure of the lobes 115 to raise the translatable wall portion 38 in a manner such as shown in Figs. 1, 3, and 6.

One of the features of the invention is that the lobes 115 do not apply a simple vertical movement to the member 38, but instead produce rhythmic waves in the member 38 which are

transmitted to the contacting portion of the patient's body. For example, assuming that the member 70, Fig. 3, is rotating in counterclockwise direction, when a lobe 115 moves upward and leftward from the position 115a thereof toward the position in which it is shown in full lines, it will elevate that portion of the translatable wall 38 disposed directly thereabove, as indicated by dotted lines 120. This hump or wave 120 will travel leftward as the lobe travels from the position 115a toward the position in which it is shown in full lines. Then, as leftward movement of the lobe continues across the lower face of the belt 42, the wave will move toward and into the position indicated by dotted lines 115b and thereafter will subside. Accordingly, each pressure application from the pad 39 to the patient consists of a wave which arises at one point, travels longitudinally and then subsides. Such wave produces a beneficial massaging action, and such wave may be caused to travel headward or footward by reversal of the motor 71. The wave motion described in the foregoing is especially valuable for abdominal treatment, and has great value as a means for deep massage of the abdominal viscera in addition to its other important therapeutic usages. A further feature of the device is that it constitutes a very satisfactory table for use in making spinal adjustments. When so used, the patient is placed in prone position with the crest of the raised pad 39 engaging the anterior portion of the patient opposite a point along the spine slightly inferior to the subluxation which is to be corrected. The patient is then properly supported for an effective adjustment, but the support is yieldable due to the fact that the yielding of the springs 49 will permit a yielding of the translatable wall portion 38 of the platform 21.

The length of movement of the platform 21 determines the length of the area of the patient's body which will be subjected to the rhythmic wave motion of the pad 39 when the device is in operation. When the block 90 is raised on the lever 87 to its fullest extent, as shown in Fig. 3, maximum longitudinal movement of the platform 21 is obtained and the specific wave and/or vibratory therapy of the device will traverse an area of the patient 130, shown on the device, from the hip region to the lower margin of the axilla. When the block 90 is lowered from the position in which it is shown in Figs. 3 and 8 to the position at the lower end of the channel 89 wherein the axis of the pin portion 93 will be aligned with the axis of the member 88 on which the lever swings, the platform 21 will remain stationary and there will be no progressive shifting of the area of application of the waves to the body, thereby providing spot treatment instead of extended treatment.

I claim as my invention:

1. In a therapy device of the character described, the combination of: supporting means; a patient receiving platform carried by said supporting means, said platform having a portion which is translatable in vertical direction; pressure means for applying upward pressure waves to a limited portion of said translatable portion of said platform; means for locally applying heat to the patient on said platform in such manner as to heat body portions positioned adjacent said translatable portion of the platform; and means for relatively moving said platform and said pressure means whereby different por-

tions of said translatable portion will be moved vertically by said pressure means to act on the heated body portions.

2. In a therapy device of the character described, the combination of: supporting means; a patient receiving platform carried by said supporting means, said platform having a portion which is translatable in vertical direction; pressure means for applying upward intermittent impulses to a limited portion of said translatable portion of said platform; and means for relatively moving said platform and said pressure means in timed relation lengthwise of said platform whereby different portions of said translatable portion will be moved by said pressure means.

3. In a therapy device of the character described, the combination of: supporting means; a patient receiving platform carried by said supporting means, said platform having a portion which is translatable in vertical direction; pressure means for applying upward pressure impulses of relatively low frequency to a limited portion of said translatable portion of said platform; means for applying impulses of relatively high frequency to said platform; means for varying the intensity of said relatively low frequency impulses; means for varying the intensity of said relatively high frequency impulses; and means for relatively moving said platform and said pressure means whereby different portions of said translatable portion will be moved by said pressure means.

4. In a therapy device of the character described, the combination of: supporting means; a patient receiving platform carried by said supporting means, said platform having a portion which is translatable in vertical direction; pressure means for applying upward pressure impulses of relatively low frequency to a limited portion of said translatable portion of said platform; means for applying impulses of relatively high frequency to said platform; means for varying the intensity of said relatively low frequency impulses; and means for relatively moving said platform and said pressure means whereby different portions of said translatable portion will be raised by said pressure means.

5. In a therapy device of the character described, the combination of: supporting means; a patient receiving platform carried by said supporting means, said platform having a portion which is translatable in vertical direction; pressure means for applying upward pressure impulses of relatively low frequency to a limited portion of said translatable portion of said platform; means acting through said pressure means for applying impulses of relatively high frequency to said platform; means for varying the intensity of said relatively low frequency impulses; and means for varying the intensity of said relatively high frequency impulses.

6. In a therapy device of the character described, the combination of: supporting means; a patient receiving platform carried by said supporting means, said platform having a portion which is translatable in vertical direction; pressure means for applying upward pressure waves of relatively low frequency to a limited portion of said translatable portion of said platform; and means acting through said pressure means for applying impulses of relatively high frequency to said platform.

7. In a therapy device of the character described, the combination of: supporting means; a patient receiving platform carried by said supporting means, said platform having a portion which is translatable in vertical direction; a supporting member carried by said supporting means under said platform; means for resiliently urging said supporting member upwardly toward said platform; a lobular member rotatably supported on said supporting member; and means for rotating said lobular member so that the lobes thereof will engage and lift said translatable portion of said platform.

8. In a therapy device of the character described, the combination of: supporting means; a patient receiving platform carried by said supporting means, said platform having a portion which is translatable in a vertical direction; a supporting member carried by said supporting means under said platform; spring means for resiliently urging said supporting member upwardly toward said platform; translating means on said supporting member operative to intermittently apply upward movement to said translatable portion of said platform; and adjusting means for varying the stress in said spring means whereby the upward pressure of said translating means against said translatable portion may be varied.

9. In a therapy device of the character described, the combination of: supporting means; a patient receiving platform carried by said supporting means, said platform having a portion which is translatable in a vertical direction; a supporting member carried by said supporting means under said platform; spring means for resiliently urging said supporting member upwardly toward said platform; translating means on said supporting member operative to intermittently apply upward movement to said translatable portion of said platform; adjusting means for varying the stress in said spring means whereby the upward pressure of said translating means against said translatable portion may be varied; and means for vibrating said supporting member whereby vibration will be transmitted through said translating means to said translatable portion.

10. In a therapy device of the character described, the combination of: supporting means; a patient receiving platform carried by said supporting means; pressure applying means under said platform for intermittently applying upward pressure; and means for horizontally moving said platform relatively to said pressure applying means comprising a lever hinged at one end, means for swinging said lever back and forth, a link having one end thereof connected to said platform, and means for connecting the other end of said link selectively to points along said lever.

11. In a therapy device of the character described, the combination of: supporting means; a patient receiving platform carried by said supporting means having an opening therein; a flexible wall structure disposed in said opening; means for resiliently applying tension to the underside of said wall structure; and mechanism positioned below said platform intermittently deflecting in an upward direction a portion of said wall structure against the action of said tensioning means.

RICHARD THOMAS.
